INVENTOR,

William Gorman

UNITED STATES PATENT OFFICE.

WILLIAM GORMAN, OF NEW BRITAIN, CONNECTICUT, ASSIGNOR TO THE RUSSELL AND ERWIN MANUFACTURING COMPANY, OF SAME PLACE.

DESIGN FOR BUTT-HINGE.

Specification forming part of Design No. 7,018, dated December 9, 1873; application filed November 15, 1873.
[Term of Patent 14 years.]

CASE F.

To all whom it may concern:

Be it known that I, WILLIAM GORMAN, of New Britain, in the county of Hartford and State of Connecticut, have invented a new Design for Butt-Hinge for Doors, &c.; and I do hereby declare that the following specification, taken in connection with the drawings making a part of the same, is a full, clear, and exact description thereof.

Figure 1 represents the two plates of the butt-hinge opened outward, showing the inner face of the plates P P; and Fig. 2 represents the two plates P P shut together, showing the outside face of one of said plates.

The design for said inside face of the butt consists more particularly of a wide border, D, extending entirely around the edge of each plate, and an inner narrow division-line, E, the intervening space being marked or ornamented with diagonal division-lines S and suitable scroll-work H, or other ornamental

figures. The design for the outside face of said plates consists of a wide border, L, around the exposed portion of this side of the plates, said border inclosing an ornamental figure consisting of a grouping of a rosette, R, scrolls S, and leaf-work T. The barrel B of the butt, which incloses the pivot, is ornamented by intersecting cross-lines, forming lozenge shapes a, with spots V, inclosed with a vertical seam, I, at the back, a wide band, k, at the top and bottom, and a narrow band, n, at the middle on each part.

What I claim as my invention, and desire to secure by Letters Patent, is—

The design for a butt-hinge, substantially as shown and described.

WILLIAM GORMAN.
